TRAY DISPLAY AND CONTAINER

William A. Ringler, Wayne, Pa., assignor to National Folding Box Company, New Haven, Conn., a corporation of New Jersey

Application July 19, 1940, Serial No. 346,308

2 Claims. (Cl. 206—44)

The present invention relates to improved displays, provided with a tray for receiving and displaying merchandise.

Preferred embodiments of the invention are of the collapsible type, the setting up of the display from collapsed status being readily afforded by mere shifting of relative positions of certain component parts accompanied by the movement of certain other panels for effecting stable positioning of the component panels, and providing a tray part for receiving and displaying merchandise.

More specifically, the invention comprises a back panel, the vertical height of which, when the display is in set-up status, may be as preferred. Such back panel is connected with a bottom panel and in turn with a front panel, to the upper portion of which, and more specifically to the upper edge portions of such front panel, are connected oppositely disposed side panels which extend horizontally from the front panel to the back panel. Integrally connected with each side panel is a panel—each termed for convenience a tray side panel—which, when the display is set up, is swung downwardly about its score line toward, and preferably engaging the bottom panel; these tray side panels cooperate with the respective portions of the front and back panels disposed between the horizontal side panels, to form the tray of the display.

Desirably, the rear edge portions of the tray side panels are locked in stable position, as in suitable recesses provided in the back panel. Preferably, the said tray side panels serve further to stabilize the display when in set-up status by reinforcing the front panel by engagement with the inner face of the front panel.

One type of preferred embodiment of the invention has its back panel extending upwardly, and also its front panel, at an angle to the vertical receding, i. e., tilted from the observer viewing the display from its front, thus adding artistic quality to the display.

Another type of preferred embodiment of the invention is coordinated as to its component panels, to have the back panel extending upwardly substantially vertically, the front panel extending either substantially vertically or at an angle to the vertical, as preferred.

Further features and objects of the invention will be more fully understood from the following detail description and the accompanying drawings, in which:

Fig. 1 is a front perspective view of a preferred form of tray or display embodying the invention;

Fig. 2 is a vertical sectional view taken on line 2—2 of Fig. 1;

Fig. 3 is a plan view of the blank from which the tray display shown in Figs. 1 and 2 is formed;

Fig. 4 is an edge view of the blank of Fig. 3, folded upon itself and glued, and constituting in collapsible status the set-up tray display illustrated in Fig. 1;

Fig. 5 is a front perspective view of another preferred embodiment of the invention;

Fig. 6 is a vertical sectional view on line 6—6 of Fig. 5;

Fig. 7 is a plan view of the blank of the tray display shown in Figs. 5 and 6.

Referring to Figs. 1 and 2 of the drawings, the tray display, indicated 10 generally, comprises a tray portion 11 suitably contoured and dimensioned for receiving articles for display or sale. The contour and dimension of the tray 11 of the embodiment as illustrated in Figs. 1 and 2 are adapted for receiving articles of the nature of cans of smoking tobacco, cartons containing tubes or cans of tooth powder, pharmaceutical products.

The tray display illustrated in Figs. 1 and 2 comprises further a back panel 12 applicable for bearing advertising indicia and/or ornamentation, desirably related to the articles disposed within the tray 11.

For display purposes, it is also desirable that the back panel 12 extend vertically upwardly at an angle, recede from the observer viewing the display and its contents from the front, the angle of recession, as appears from Fig. 2 being subject to variation as desired.

In the more preferred embodiments of the invention the front panel 13 extends also at an angle to the vertical, and may be substantially parallel to the receding back panel 12.

The tray display, as illustrated, is formed of a collapsible blank, as appears more fully hereinafter; however, the invention is not limited to such collapsible feature.

Structurally, the collapsible tray display 10, as appears in set-up status in Figs. 1 and 2 and in flat blank in Fig. 3 and in collapsed status in Fig. 4, comprises the lower back panel 14, hingedly connected to the bottom panel 15, in turn hingedly connected to the stated front panel 13. To oppositely related upper portions of the front panel are connected oppositely disposed and horizontally extending side panels 16, 16. Specifically these side panels 16, 16 are integrally, i. e., hingedly connected to oppositely related portions of the upper edge of the front panel 13, as appears from Figs. 1 and 2.

At the rear the horizontally extending side panels 16, 16, are connected, specifically integral-
ly hingedly connected, to the upper back panel 12, aforesaid, the upper edge portion of the lower back panel 14, overlapping the lower edge portion of the upper back panel 12 and suitably secured thereto to one another, as by glue or other adhesive, staples, etc.

Hingedly connected to the respective inner edges of the horizontal side panels 16, 16, are tray side panels 17, 17, which at the stage of setting up the display are turned downwardly, i. e., toward the bottom panel 15; and preferably are dimensioned to engage the bottom panel 15. These tray side panels 17, 17, together with the intermediate disposed portions of the back panel 14 and front panel 13, define the tray 11 of the display.

To stabilize the display when set up, the back panel 14 is provided with suitably located and dimensioned slots 14a, 14a, or equivalent recesses and the rear edge portions 17a, of the tray side panels 17, 17, are contoured to be "snapped" into said recesses 14a, 14a, respectively. Further, stabilization of the display is had by suitably contouring the front edge portions 17b, 17b, of the tray side panels 17, 17, to engage the inner face of the front panel 13.

In an embodiment of the invention of the collapsible type having its back panel and its front panel extending at an angle to the vertical and formed from a single blank, as appears from Fig. 3, the respective front edges 17b, 17b, of the tray side panels 17, 17, are severed at mutually re-entrantly related angles and to the longitudinal center line of the blank, the extent of each angle determining the extent of the angle to the vertical of the back panel and the front panel when the display is set up. It is observed that the angle of severing at the edges 17b, 17b, of the tray side panels 17, 17, results in tilting of the front panel 13 at the front of the tray 11, a feature adding to the attractiveness of the display.

If desired, and as is illustrated in Figs. 1 and 2, an easel-like formation is had at the rear of the bottom panel 15, by providing a line of severing, see 15a, shown of arcuate configuration. This gives rise also to a corresponding cut-out, as indicated at 15a, see Fig. 1, which is normally concealed when any articles are placed in the tray 11.

The indicated extension 12a, shown at the upper edge of the display, see Fig. 1 is optional.

The blank of the collapsible type of tray display, shown in Fig. 3, is largely apparent from the above detail description of Figs. 1 and 2. To complete the description of the indications appearing in Fig. 3, the line 17a is a line of severing; the lines 18, 18, are score lines, likewise the lines 19, 19; the line 20 is a score line as also the lines 21, 21. The stippling indicated at 22, represents glue or other adhesive or other form of attachment, which is employed for securing the upper edge portion of the lower back panel 14 to the lower edge portion of the upper back panel 12, see 22a in Fig. 2, and indicated, also by 22a in Fig. 4, which shows in edge view the blank of Fig. 3 folded and secured as above set forth and constituting the tray display of Figs. 1 and 2 in collapsed status.

The folding of the blank of Fig. 3 and gluing of the same, as aforesaid, may be carried out on a conventional collapsible box making machine.

As appears from Figs. 3 and 4, any printing or other impressions desired upon the faces of the back panel 12, and/or front panel, and/or side panels 16, 16, may be performed simultaneously at a single operation.

The embodiment shown in set-up status in Figs. 5 and 6, and in blank in Fig. 7, follows generally that shown in Figs. 1 through 4, described herein-

above, and like parts are designated by like reference characters. The embodiment shown in Figs. 5 and 6 is characterized by the back panel 12 and front panel 13 extending substantially vertically when the display is set up, effected by contouring the rear edges 17a, 17a, of the tray side panel 17, 17, see Fig. 7, by severed lines forming mutually re-entrantly related angles and at an angle to the longitudinal center line of the blank. The front edges 17b, 17b of the tray side panels 17, 17, are contoured "square" by lines of severing applied to the blank.

In the embodiment shown in Figures 5, 6 and 7, the panel 12, if desired, may serve as the cover or closing panel of the tray display by swinging the panel 12 downwardly to effect closure, which may be facilitated by providing a score line at the hinge line, which may be located as indicated at 22b, in Fig. 7.

Whereas I have described my invention by reference to specific forms thereof, it will be understood that many changes and modifications may be made without departing from the spirit of the invention.

I claim:

1. In a display formed of a single blank of paper stock or the like, the combination of an upper back panel, mutually spaced side panels; a front panel; a bottom panel; and a lower back panel; said panels being hingedly connected with one another in the order named and said lower back panel being connected to said upper back panel; downwardly extending tray wall panels cut from the material of the blank between said side panels and hingedly connected to inner edges of said mutually spaced side panels along fold lines and extending toward the bottom panel to provide a tray for reception of goods to be displayed; the front edges of said tray wall panels being cut at an angle to the vertical whereby upon engagement with the inner face of said front panel, said front panel is tilted rearwardly as viewed from the front of the display and said lower and upper back panels are correspondingly tilted; the rear cut edges of the tray walls being at right angles to said fold line; said lower back panel being provided with slots to respectively freely receive the rear edges of said tray wall panels and thereby maintain the display in tilted set-up status.

2. In a display formed of a single blank of paper stock or the like, the combination of an upper back panel, mutually spaced side panels; a front panel; a bottom panel; and a lower back panel; said panels being hingedly connected with one another in the order named and said lower back panel being connected to said upper back panel; downwardly extending tray wall panels cut from the material of the blank between said side panels and hingedly connected to inner edges of said mutually spaced side panels along fold lines and extending to the bottom panel to provide a tray for reception of goods to be displayed; the front edge of each of said tray wall panels defining a straight line and cut for engagement with the inner face of said front panel; the rear cut edge of each of the tray walls defining a straight line at such an angle with respect to said fold lines as to intersect said lower back panels; said lower back panel being provided with slots to respectively freely receive the rear edges of said tray wall panels and thereby maintain the display in set-up status.

WILLIAM A. RINGLER.
